UNITED STATES PATENT OFFICE.

NICHOLAS RENNER, OF DEFIANCE, OHIO.

VENTILATOR.

1,342,066.

Specification of Letters Patent.

Patented June 1, 1920.

Application filed July 2, 1919. Serial No. 308,231.

To all whom it may concern:

Be it known that I, NICHOLAS RENNER, a citizen of the United States, residing at Defiance, county of Defiance, and State of Ohio, have invented certain new and useful 5 Improvements in Ventilators, of which the following is a specification.

This invention relates to a ventilating system which may be applied to houses or other 10 buildings, and also to railway cars or ships.

The invention has for an object to provide a ventilating system which may be cheaply and easily installed during the construction of the building, car or ship and 15 which operates efficiently to constantly maintain a supply of pure air therein, and to avoid entrance of smoke, dust, cinders or the like.

For further comprehension of the invention, and of the objects and advantages 20 thereof, reference will be had to the following description and accompanying drawings, and to the appended claim in which the various novel features of the invention 25 are more particularly set forth.

Figure 1 of the drawings is a longitudinal sectional view of a railway passenger car body having the invention embodied therein, this view being taken on the line 1—1 30 of Fig. 4.

Fig. 2 is a similar view taken on line 2—2 of Fig. 4.

Fig. 3 is a horizontal section taken on the line 3—3 of Fig. 4.

Fig. 4 is a transverse section through the car body, this view being on a larger scale than Figs. 1, 2, and 3.

Fig. 5 is an end view of the car body drawn to the same scale as Fig. 4.

Fig. 6 is a vertical sectional view of a building having the invention embodied therein.

Fig. 7 is a horizontal section on the line 7—7 of Fig. 6.

In Figs. 1 to 5 of the drawing, I have shown my improved ventilating system applied to a car of ordinary construction, the doors, windows or other fittings being omitted since they have no relation to the 50 present invention and illustration of such fittings is not necessary for a proper understanding of the invention.

The car body here shown is of ordinary type with a floor 1, sides 2, ends 3 and roof 55 4, the latter having the usual central raised portion 4'.

According to my invention the side portions of the roof are provided with longitudinally extending channels 5 and 6, the former being the inlet channel and the latter the outlet channel. 60

The inlet channel 5 communicates at its ends with the upper ends of vertical channels 7 and 8 in the end walls 3, the lower ends of these vertical channels being located 65 near the floor and opening outwardly through the end walls. Screens 9 cover the entrance openings to these channels.

The outlet channel 6 opens directly at its ends through the end walls of the car as 70 clearly shown in Figs. 2 and 3. These longitudinal channels 5 and 6 communicate with the interior of the car through small openings 10 and 11 respectively which are formed in the under walls of the channels 75 and are spaced throughout the area thereof.

In operation of the ventilating system the fresh air enters through the screens 9 into the vertical channels 7 and horizontal channel 5 and flows through the openings 80 10 into the interior of the car. The air afterward passes through the openings 11 into the channel 6 and out through the latter.

The inlet channel 5 is provided with a 85 damper or shutter 15' at each end thereof, these shutters being opened or closed by means of rods 16' pivotally connected at their upper ends to the shutters and extending at their lower ends through spring 90 clip brackets 17' of well known construction upon the end walls of the car by which the rods are held in adjusted position, the rods extending through suitable apertures in the inner wall of the channel 5. 95

As will be apparent the device can be easily regulated by the conductor by simply adjusting the rods or handles 16, the shutter at the forward end of the car being closed, and the shutter at the rear end being opened 100 as much as desired to secure the proper ventilation, thus a constant supply of fresh air being insured while cinders, smoke, dust or the like are excluded.

In Figs. 6 and 7, I have shown my improved ventilating system applied to a building of ordinary construction having vertical walls 15 and 15', a ground floor 16, above which are the usual horizontal ceiling and flooring partitions 17. A vertical 105 110 channel 18 extends upwardly in the wall 15 from a point near the ground floor 16, this

channel having at its lower end an outwardly opening screened mouth 19.

A second vertical channel 20 is formed in the wall 15' and extends upwardly from the lower ceiling and floor partitions 17.

Formed in each of the partitions 17 are a pair of horizontal channels 21 and 22 which communicate by the branches 23 and 24 with the inlet and outlet channels 18 and 10 20 respectively.

These horizontal channels 21 and 22 communicate with the rooms below them by means of the small openings 25 and 26 leading through the ceilings of the rooms into 15 the channels.

In operation fresh air enters through the screened mouth 19 into the vertical channel 18 flowing into the horizontal channels 21 and through the openings 25 into the interior of the building. The used air passes 20 outwardly through the openings 26 into the horizontal channel 22, thence to the vertical channel 20 and upwardly through the latter to the outside, it being understood 25 that inlet channel 18 is closed to the outer air at its upper end and outlet channel 20 opens to the outer air at its upper end.

It will be understood, of course, that the particular arrangement will carry according 30 to the kind of building car, ship or

other structure in which it may be embodied, the invention being particularly suitable for application to schools, hospitals and like buildings. Where desired a filler of suitable construction can be applied to 35 the intake opening to purify the air as it enters. It will be obvious of course that shutters such as illustrated in Figs. 1 and 4 may be applied to the air inlet passages when the invention is embodied in buildings, ships or any other structure. 40

Having thus described my invention what I claim as new and desire to secure by Letters Patent, is:—

A railway car having a roof, a pair of 45 parallel channels extending from end to end thereof, one of said channels opening directly through the ends of the car, the end walls of said car being provided with lateral channels communicating at their upper ends with the other of said parallel channels and at their lower ends with the exterior of the car, the car roof being formed with passages leading from the interior of the car to the said parallel channels. 50 55

In testimony whereof I have affixed my signature.

NICHOLAS RENNER.
